CLAIM

The ornamental design for an anti-vermin shield for an airplane wheel, as shown and described.

DESCRIPTION

FIG. 1 is a top perspective view of an anti-vermin shield for an airplane wheel showing my new design;

FIG. 2 is a front elevational view thereof, the rear being a mirror image of the front shown in FIG. 2;

FIG. 3 is a side elevational view thereof, the side opposite being a mirror image of the side shown in FIG. 3;

FIG. 4 is a top plan view thereof; and,

FIG. 5 is a bottom plan view thereof.
